UNITED STATES PATENT OFFICE.

BURT E. TAYLOR, OF MOUNT VERNON, NEW YORK, ASSIGNOR TO THE BORDEN COMPANY, OF NEW YORK, N. Y., A CORPORATION OF NEW JERSEY.

CAN-CAPPING MACHINE.

Application filed July 24, 1920. Serial No. 398,701.

To all whom it may concern:

Be it known that I, BURT E. TAYLOR, a citizen of the United States, and a resident of Mount Vernon, county of Westchester, 5 and State of New York, have invented certain new and useful Improvements in Can-Capping Machines, of which the following is a specification.

My present invention relates to improvements in machines adapted to assist in the "capping," sometimes hermetic, of metallic cans, of well-known types usually employed as containers of liquid, or semi-liquid goods, as for example condensed or concentrated 10 milk, etc., such cans being usually cylindrical and their heads containing a relatively small therewith concentric opening closable by a metallic cap which after being positioned with relation to said opening 15 is crimped, or distorted, to produce a tight joint or seam with the material of the can surrounding the opening.

Hitherto cans and caps of the class referred to have been largely employed of 20 forms, and construction, such as are disclosed, for example, in U. S. Letters Patent No. 757,842 to Frank Rogers, or No. 1,188, 25 639 to Le Roy Fish (see particularly Figures 11 and 12 of the drawings of the latter) and have been united or sealed by aid 30 of such means as are disclosed in the former, the metal of the head of the can being shaped so as to provide, circumferentially of said opening, a continuous "neck" flange 35 projecting outwardly at right angles from the surface of the head, and the metallic cap comprising a therefrom shaped, correspondingly, circumferentially, continuous therefrom outwardly flaring flange which when 40 the cap has been positioned in the opening or "neck" overlies the "neck" flange and is thereafter crimped down upon and into continuous close contact with the latter to produce the seal and thus the "capping" of 45 the can. Uniform impartation of required strength and integrity to said neck flanges has proved difficult and undesirably uncertain and expensive, relatively costly metal and perfectly operating dies being indis- 50 pensable to prevent too many leaks from cracking of the neck flanges in their making, or during the crimping. The devices

required to successfully crimp together these former styles of flanges have hitherto required a multiplicity of moving parts 55 such as are undesirable because of rapid wear and difficult readjustments, or expensive replacements, and the labor and power to work them has been excessive. Furthermore the resulting seals have been unreliable 60 as regards atmospheric penetration, or, as is now of growing consequence in the class of goods referred to, as regards capacity to maintain, after sealing, the exhaust, or vacuum, under which the goods are canned. 65

My present invention is designed to, and does importantly obviate the referred to disadvantages of previous procedures, and its aforesaid objects I attain by aid, for example, of the mechanisms illustrated in the 70 accompanying drawings, in which—

Figure 1 is an elevation, parts of which are shown in central vertical section, of the principal parts of an apparatus designed to crimp the caps as per my invention and 75 showing similarly a can and also a cap positioned in the opening of the latter.

Figure 2 is, on enlarged scale, a view partly in section and partly in elevation of my crimpler and its actuating spreading or 80 wedge member.

Figure 3 is, on still larger scale, a central section of my preferred novel form of cap.

Figure 4 is a similar view of said cap and of a fragment of the can and can head showing the cap positioned prior to its being 85 crimped.

Figure 5 is a plan view of my crimping tool viewed from the bottom thereof.

Figure 6 is a view, partly in elevation and 90 partly in central section, illustrative of the relative positions of the can, the cap, and of my crimpler just prior to the beginning of the crimping operation.

Figure 7 is, on enlarged scale, a view illustrating of the relative positions of the parts at the close of the crimping operation, the cap and a portion of the can being in this figure shown in central section, part of the wedge in elevation, and also a half of 100 the lower part of my crimpler.

Similar reference numerals refer to similar parts throughout the several figures.

My crimping tool proper, indicated com-

prehensively as 8, is of longitudinally extended cylindrical form and comprises a rigid body portion, 9, having a therewith concentric bore, 9', and a relatively expandible extension, 10, composed of a plurality of mutually separated, or slightly spaced-apart, outwardly and inwardly movable members or fingers, 10', having their free ends normally relatively closely approximated to each other as shown, and containing between them a tapered extension, 10'', of the bore 9'. The tool is preferably unitary and metallic, the fingers being dimensioned and positioned, as shown, so as to possess yield and resilience transversely of the longitudinal axis of the tool. They are preferably produced by appropriately slitting the sides of the extension 10, and thus serve to partially enclose the tapered extension 10''. Each of these fingers carries adjacent its free end an outwardly presented crimpler blade, or crimping edge, 11, and also, in a plane apart, from and in parallelism with the plane of said edge an outwardly projecting retaining flange 12. It will be noted that as shown in Fig. 2 of the drawings and as is preferable and usually important, the surface of the crimping blade is inclined relatively to the thereto opposite surface of the flange, thereby providing an inwardly extending and contracting space, or recess, between the said surfaces for therein reception of metal of the can top and of the thereon to be crimped metal of the cap when the fingers are forced outwardly as hereinafter described, the result being that said metals are then progressively pressed, or clamped, together thereby contributing to the air-tightness of the joint. It follows that my tool may be said to carry a plurality of cooperating crimping edges and of therewith co-operating retaining flanges simultaneously movable radially, outwardly and inwardly relatively to its central longitudinal axis. It will also be noted that, as is preferable in most cases, the surfaces of the flanges which are opposite to the said inclined surfaces of the crimping blades are located more angularly, in this instance normally, in a plane at right angles, to said axis and that consequently the outward movement of the retaining flanges, 12, smoothes, or as it were irons out, the peripheral edges or flanges of the caps, radially outwardly in conformity with the underlying parts or tops of the cans thereby perfecting completeness of contact and improving appearance. To impart outward movement to the crimping edges and simultaneously and equally to the retaining flanges, I provide a spreader arbor, or wedge, 13, longitudinally reciprocatable within said bores and preferably correspondingly dimensioned and having a complementarily tapered portion 13' as shown

in Figure 2. I provide means to support my crimpler tool and means to support a can 14 with their respective central longitudinal axes in register and in such fashion that the one may be, while so positioned, relatively movable toward and from the other. In the present instance, in which the can is so movable towards the relatively thereto stationary crimpler tool, I support the can upon a reciprocatable block, or table, 15, carried by a threaded spindle, 16, (Fig. 1) suitably transversely rotatably supported and screwed upwardly or downwardly by any well known means (not shown) so as to raise, or move, the can to the required degree towards the crimping tool, as hereinafter described. The crimping tool is, relatively to said table, stationarily carried by any appropriate frame, 17, to which it is secured in any convenient manner. An arm, 17', of the frame 17, carries, pivotally connected therewith as at 18 a lever, 19, having a handle, 20. The un-tapered upper portion of the arbor, or wedge, 13, carries a block, 21, within which passing through a therein slot, 22, is rockably held by a pivot, 22', the lever, 19, the construction being such that rocking of the lever will impart reciprocation to the arbor, or wedge, 13 within, and longitudinally of, my crimpler tool.

To arrest the reciprocatory downward movement of the wedge, or arbor, 13, at a predetermined, required point, I provide in the path of the lever, 19, an adjustable stop, 23, consisting, in this instance, of, as shown, a screw bolt, revolvably carried by, and projecting above, the frame 17, by turning the head, 23', of which the height of the operative end of the stop is adjustable to check, or arrest, the descent of the lever, 19, and thus the downward movement of the wedge, or spreading arbor, 13.

The importance, if not indispensability, of my said stop so constructed as to thus permit of micrometric adjustment of the range of the above described outward movements of my crimping blades and therewith associated flanges, follows from the fact that unless thus very exactly adjusted according to varying thickness of caps and cans there is danger of their becoming jammed in the inwardly contracting above described recesses between the blades and the flanges.

The cap, designated in its entirety by 24, is of the form and construction above referred to, being usually of metallic composition, for example of sheet metal, and consisting principally of a disc-like body portion, 24', to which has been preferably imparted a concavo-convex, or dished, conformation, as shown, and a therefrom extending annular neck, 24'' (dimensioned to closely fit the usual, relatively small, cir-

cular opening, 14', in the head of, and concentric with, the can 14) and surrounded by the usual therefrom outwardly flaring annular flange, 24''.

5 Operation: The cap is positioned in the opening in the head of the can as shown in Figures 1, 4, etc. The can 14, being positioned upon the table 15 in the above described relation to the central longitudinal 10 axis of the crimping tool, is raised by turning the spindle 16 until the above described crimping edges, 11, have been brought below the level of the head, 14'', i. e., brought within the interior of the can and consequently also down into the neck of the cap so that the crimping edges are radially forcible simultaneously at a plurality of points against the interior of said neck. The position of the parts at this stage is 20 indicated in Figure 6 of the drawings. It will be noted that the relation of the projecting flanges 12 relatively to the crimping is predeterminedly such that, at this stage, the flanges bear directly upon the top of the 25 flange 24''' of the cap, thereby holding it firmly in position. The operator then presses the handle 20 of the lever 19, whereby the wedge, or arbor, 13, is forcibly pushed downward, thereby spreading the 30 therewith contacted fingers 10', and correspondingly, simultaneously and equally forcing the crimping edges against the neck, 24'', of the cap. The construction and positioning of the parts is such that this results in distorting, swaging, or crimping the neck of the cap as indicated in Figure 35 7, thereby producing a joint or seam between the cap and the head of the can so tight and effective as normally to be hermetic.

The simplicity, economy and durability of my apparatus and of its constituent elements, particularly the crimping fingers and edges, is great as will be obvious from the 45 above references to the prior art. It will be understood that my above described crimping tools may be operated by other than hand power, and also in groups simultaneously upon pluralities of caps and cans, 50 and that my invention is not limited to the particular forms and construction shown in the drawings.

The above referred to impartation of a dished, or concavo-convex form of the bottom or body-portion, 24', of the cap constitutes a part of my invention, as I believe this to be novel and of importance in aid of producing a seal of the hermetic character described and with minimum risk of injury 60 to the cap. The surplus material provided by the form referred to supplies to the cap what is required to complete most effectually the seam and results in the impartation of an improved appearance to the final product, 65 the body portion of the cap being brought

into a single plane and in parallelism with that in which is the head of the cap, as shown in Figure 7.

It will be observed that my invention advantageously dispenses entirely with the 70 above referred to former neck flange in the head of the can.

Having now described my invention, what I claim as new and desire to secure by Letters Patent is the following, viz: 75

1. In apparatus for securing metallic caps to metallic cans, a cap-holding, ironing, and crimping tool comprising a plurality of outwardly expandible resilient fingers, each carrying in one plane adjacent its free end 80 an outwardly presented crimping blade, and also, in another plane, less adjacent to said free end, an outwardly extending cap-retaining, and ironing, flange; means to force and retain said flanges against the top of the 85 cap; and means to meanwhile force the fingers outwardly, whereby a part of the cap is retained in place and smoothed or ironed by the flanges while another part of the cap is being distorted by the crimping 90 blades.

2. In apparatus for securing metallic caps to metallic cans, a cap-holding, ironing, and crimping tool comprising a plurality of outwardly expandible resilient fingers, each 95 carrying in one plane adjacent its free end an outwardly presented crimping blade, and also, in another plane, less adjacent to said free end, an outwardly extending cap-retaining, and ironing, flange, having its operative 100 surface disposed in a plane at right angles to the central longitudinal axis of the tool; means to force and retain said flanges against the top of the cap; and means to meanwhile force the fingers outwardly. 105

3. In apparatus for securing metallic caps to metallic cans, a cap-holding, ironing, and crimping tool comprising a plurality of outwardly expandible resilient fingers, each carrying in one plane adjacent its free end 110 an outwardly presented crimping blade, having an operative surface disposed in a plane inclined to the central longitudinal axis of the tool, and also, in another plane, less adjacent to said free end, an outwardly extending cap-retaining, and ironing, flange, having its operative surface disposed in a plane angular to said first mentioned plane; means to force and retain said flanges against the top of the cap; and means to 115 meanwhile force the fingers outwardly.

4. In an apparatus for securing metallic caps to metallic cans, a cap-holding, ironing, and crimping tool comprising a plurality of resilient outwardly movable fingers each 125 carrying adjacent its free end an outwardly presented crimping blade and also a therefrom spaced-apart more outwardly extending retaining flange; means to position and hold the caps in contact with said flanges; 130

and means to force the fingers outwardly whereby the cap is retained in place and portions thereof are smoothed or ironed by the flanges, and simultaneously distorted by 5 the blades.

5. In apparatus for securing metallic caps to metallic cans, a cap-holding, ironing, and crimping tool comprising a plurality of fingers movable outwardly from the central 10 longitudinal axis of said bore and each carrying an outwardly extending flange hav-

ing a flat operative surface normally disposed in a plane angular to the central longitudinal axis of the bore; means to position and hold the caps in contact with said 15 operative surfaces of the flanges; and means to meanwhile force the fingers outwardly whereby the cap is retained in place and portions thereof are simultaneously smoothed or ironed by the flanges.

BURT E. TAYLOR.
